UNITED STATES PATENT OFFICE.

SETH A. CRONE, OF EAST ORANGE, NEW JERSEY.

BRAKE BEAM FOR RAILWAY CARS.

Application filed June 12, 1922. Serial No. 567,578.

To all whom it may concern:

Be it known that I, SETH A. CRONE, a citizen of the United States, and a resident of East Orange, in the county of Essex and

5 State of New Jersey, have invented certain new and useful Improvements in Brake Beams for Railway Cars, of which the following is a specification.

The invention pertains to trussed-beams 10 for railway-cars and especially to a novel strut interposed between the compression and tension members of the beam.

One object of the invention is to provide 15 a highly efficient strut in forged metal; a further object of the invention is to provide a novel one-piece forged metal strut; a still further purpose of the invention is to provide a novel construction at the front end of the strut to receive the truss-member, and

20 a further purpose of the invention is to provide a novel construction at the back end of the strut for securing the same to the compression member of the beam. The strut of my invention possesses great strength, durability and efficiency without undue weight of

25 metal and also special advantages in respect to its readiness of manufacture and application to position and capability of withstanding the severe treatment to which struts 30 of trussed brake-beams are subjected. The two side portions of my strut stand at the usual angle of forty degrees from the vertical, and at the forward end of the strut the metal thereof has, without extra pieces

35 of metal, a bearing recess of novel construction formed therein to receive the central portion of the truss-rod, this bearing recess in respect to its formation being essentially novel and serving to strengthen the forward end of the strut and also to direct the strains of the truss-rod longitudinally of the side members of the strut. I preferably form the strut out of a single bar of forged metal and at the back end of the strut the ends of the bar are preferably brought into interlocking relation at the back of the compression member.

The invention will be fully understood 40 from the detailed description hereinafter presented, reference being had to the accompanying drawings, in which:

Fig. 1 is a top view, partly broken away, of a trussed brake beam for railway cars embodying my invention;

45 Fig. 2 is a side elevation, partly broken

away, of the strut, with the compression and tension members shown in vertical transverse section on the dotted line 2—2 of Fig. 1;

Fig. 3 is a back end view of the strut; 60

Fig. 4 is a front end view of the strut;

Fig. 5 is a top view, partly broken away and partly in section, of a brake-beam showing a modified form of strut embodying a portion of my invention, the modification 65 residing in the manner of connecting the sides of the strut with the compression member;

Fig. 6 is a side elevation of the same, the compression and tension members of the 70 beam being shown in vertical transverse section;

Fig. 7 is a front end view of the strut shown in Figs. 5 and 6;

Fig. 8 is a top view, partly broken away, 75 of a brake-beam illustrating a further modification of my invention;

Fig. 9 is a side view, partly broken away, of the strut, with the compression and tension members shown in vertical transverse 80 section;

Fig. 10 is a front end view of the strut presented in Figs. 8 and 9, and

Fig. 11 is a side view of the forward 85 end of the strut as the same appears at one stage of the manufacture preparatory to forming the tension rod bearing at the forward end of the strut.

In the drawings, referring to Figs. 1 to 4 inclusive, which illustrate one embodiment 90 of my invention, 15 designates the compression member, 16 the tension member and 17 the strut of a trussed brake beam for railway cars.

The strut 17 is formed from a single 95 bar of forged metal folded on an approximately U-bend at its middle portion to provide a front end 18, corresponding properly spaced apart parallel sides 19 to receive between them the usual brake-lever, not shown, and a back end 20, the sides 19 being provided with corresponding reinforced openings 21 for the brake lever pin, and the front end 18 and back end 20 of the strut being of special and novel formation.

The front end 18 of the strut is formed with a horizontally extending elongated curved bearing or recess 22 to receive the middle portion of the truss-rod 16, and this recess 22 is formed out of the metal of 110

the strut and by depressing the forward diagonally disposed normal U-bend of the strut inwardly and rearwardly along a curved horizontal line so as to form a seat 5 or bearing for the truss-rod 16 having horizontally extending top and bottom members 23 which add to the efficiency of the seat and serve to confine the truss rod at the upper and lower edges of the same. The 10 formation of the bearing recess 22 in the manner described results in the metal at diagonally opposite portions of the forward bend of the forged bar being spread horizontally to a limited extent, as at 24, whereby 15 by a recess 22 of proper elongation is created, and as shown in Fig. 4, the said recess extends across the longitudinal planes of the angularly disposed sides 19 of the strut, whereby strains created on the strut 20 by the truss-rod are exerted longitudinally against and through the length of the sides 19. The laterally spread out portions 24 at the ends of the recess or bearing 22 are also of functional value in respect to forming 25 outwardly rolled corrugations, shown at 24, which overhang the outer flat faces of the strut-sides 19 and create a head end which adds strength and efficiency to the forward end of the strut without adding to the 30 weight of metal thereat.

At its back end the strut 17 encompasses the compression member 15, and this construction is formed by bending the free ends of the beam from which the strut is 35 formed to create a loop adapted to transversely encompass said member 15, and in accordance with my invention I form one back end 25 of the metal bar with a key-stone recess 26 and the other end of said 40 bar with a key 27 adapted to fit and interlock with said recess 26, as shown in Fig. 3, at about the middle portion of the back of the beam 15. The recess 26 and key 27 serve to lock the two free ends of the bar 45 together so as to resist being pulled apart, and as further means for securing the free ends of the bar at the back of the beam 15, I recess said beam, as at 28, and by means of a punch, depress the central portion of the key 27 into said recess, as at 50 29, thereby further securing the back end of the strut to the beam 15.

The strut shown in Figs. 1 to 4 inclusive is thus formed of one integral bar of forged 55 metal, said bar being folded and treated at its middle portion to create the forward end 18 and to form the sides 19 of the strut, while the two ends of the bar are bent to pass upon and encompass the compression member 15 and are interlocked together at the back of said beam and may be further secured in position by the provision of the depression 29, said depression as aforesaid entering the recess 28 formed in 60 the back of the beam 15. I may further

secure the ends of the bar at the back of the beam 15 by pressure applied to the opposite side edges of said ends of said bar after they have been positioned on the beam 15 or by other means. The sides 19 are 70 twisted in a known manner to give them their 40° set.

The creation of the recess 22 in the forward end of the strut in the manner described results in a special formation or 75 distribution of the metal at that end of the strut offering great resisting power, this formation involving a strengthening of the metal transversely of the end of the strut and the providing of the special upper and lower forwardly projecting portions 23 to overlap the truss-rod 16 and the lateral extensions 24 which elongate the seat and form corrugations strengthening the forward ends 80 of the strut-sides 19.

In the formation of the strut from a single bar of forged-metal, the bar is ordinarily folded at its middle portion to form a rounded or semi-circular forwardly projecting end or U-bend, and this end is horizontally depressed to create the bearing recess 22, this recess extending across the longitudinal planes of the angularly disposed sides 19, as shown in Fig. 4, and creating the outwardly pressed members 23, 24, all serving 90 to strengthen the end of the strut and tie the front ends of the sides 19 together. I am aware, however, that the folding of the forged metal bar at its middle portion to form the forward end of the strut and the creation therein of the tension rod bearing 22 may be carried out by a substantially simultaneous or continuous operation on a machine built for that purpose. The formation of the forward end of the strut is 100 new and the invention is not limited to any precise steps for producing the construction 105 described.

The strut shown in Figs. 5, 6 and 7, is numbered 30 and is formed from a single bar of forged metal manipulated to form the forward tension rod bearing end 31 and parallel sides 32. The sides 32 at their back ends, representing the end portions of the metal bar, are bent outwardly in opposite directions to form flanges 33 to lie between the flanges of the compression member 34 and be riveted to the back of said member in a well-known manner. The forward end 31 of the strut 30 is identical 110 with the forward end of the strut 17 hereinbefore specifically described and hence further description of the same is not required. I present Figs. 5, 6 and 7 to indicate that my invention is not in every instance confined to a loop formation at the back end of the strut to encompass the compression member of the beam, and it is believed, therefore, that further detailed description of the construction shown in Figs. 115 120 125 130

5, 6 and 7 is unnecessary, the modification residing in the provision of the flanges 33 instead of the loop or box formation shown in Fig. 2 at the back end of the strut.

5 The construction shown in Figs. 5, 6 and 7 also serves to denote that the sides of the strut at their back ends may be variously connected with the compression member of the beam.

10 In the construction shown in Figs. 8 to 11 inclusive, the strut, numbered 34, is formed from a single bar of forged metal bent at its middle portion to form the looped or box-like back end 35 of the strut and

15 provide the parallel sides 36 of usual character, at whose forward ends the end portions of the metal bar are bent toward each other and overlapped, as at 37, 38 in Fig. 11, and then acted on to form the forward 20 end 39 of the strut having the bearing recess 40 for the tension rod member 41. The forward end 39 of the strut 34 in essential respects corresponds with the forward ends of the struts shown in Figs. 1 to 7 inclusive, 25 and the back end 35 of the strut 34 differs from the back ends of the struts shown in Figs. 1 to 7 inclusive in that said end 35 is in one integral piece transversely encompassing the compression member 42 and 30 formed from the middle portion of the initial bar.

The inwardly turned ends or flanges 37, 38 at the forward end of the metal bar from which the strut is formed serve as a substitute 35 for the U-bend of the bar from which the struts shown in Figs. 1 to 7 inclusive is formed, and said flanges 37, 38 are treated in accordance with my invention to produce the forward strut end 39 possessing the characteristics of the strut ends 18, 31, plus the 40 additional advantage of providing an extra thickness of metal at the forward end of the strut without the forging of an additional piece to the bar from which the strut is formed. When the flanges 37, 38 are overlapped, as shown in Fig. 11, they close the forward end of the strut and initially form a box-like end extending on a diagonal plane of forty degrees from the vertical and crossing from one side 36 to the other of the strut, and the closed end thus formed I subject to an upsetting operation to form the horizontal tension rod bearing or recess 40 therein, this upsetting operation acting to

45 weld the flanges 37, 38 together and to transform them into a solid forward end 39 possessing the recess or bearing 40 and creating the lateral extensions 43 corresponding with the extensions 24 of Fig. 1 and the upper 50 and lower forwardly projecting members 44, 44 corresponding with the similar parts 23 shown in Figs. 1, 2 and 4. The lateral deflection of the metal at the forward end of the strut shown in Figs. 8, 9 and 10, 55 creates corrugations at 43 extending along

the sides 36 of the strut, this being a feature which is also present in the struts shown in Figs. 1 to 7 inclusive. The forward end of the strut shown in Figs. 8, 9 and 10 is, therefore, substantially the same 70 as the forward end of the struts shown in Figs. 1 to 7 inclusive, with the exception that by reason of the overlapping flanges 37, 38, the forward end 39 of the strut shown in Figs. 8, 9 and 10 is of increased thickness and therefore possesses greater strength than when the forward end of the strut is formed of the single thickness present at the U-bend of the initial bar.

In Figs. 1 to 7 inclusive the bar is folded at its middle portion to form the forward U-bend which is converted into the special end construction hereinbefore described to receive the tension rod member, whereas in respect to the strut shown in Figs. 8 to 11 80 inclusive the fold or bend of the initial bar constitutes the back end of the strut, while the ends of said bar are flanged and overlapped, as shown in Fig. 11, preparatory to being converted into the forward end 39 to 90 receive the tension rod member 41. In each instance the strut is formed from a single bar of forged metal manipulated or treated to provide the special forward strut-end hereinbefore described, the parallel sides between which the brake-lever is hung and means at the back end of the strut for securing it to the compression member, the operation of forming the strut from the initial bar being one which may be easily carried out at minimum expense and the resulting construction being one of high efficiency and maximum capability of resistance to strains. In each instance the sides and forward closed end of the strut initially 100 stand at a forty degree angle and in each instance said end is subjected to transversely applied pressure for deforming said end to create the horizontal tension rod bearing crossing the longitudinal planes of the sides 110 of the strut and to strengthen the forward ends of said sides, said sides at their forward portions being otherwise plain and parallel and in their initial form, being spaced apart as usual and permitting, without being lengthened, the proper play for the brake-lever.

What I claim as my invention and desire to secure by Letters Patent, is:

1. A brake-beam for railway cars comprising a compression member, a tension member and a strut of forged metal, said strut having parallel angularly-set spaced-apart sides and the forward end of the strut being depressed horizontally to form a concave bearing seat for the tension member having forwardly projecting upper and lower parts to engage said member, the depression of the metal to form said seat displacing the metal of the forward end of the 120

- strut laterally, and said sides at their forward portions being otherwise plain and parallel and in their initial form.
2. A brake-beam for railway cars comprising a compression member, a tension member and a strut of forged metal, said strut being in one integral bar having parallel angularly-set spaced-apart sides and the forward end of the strut being depressed horizontally to form a concave bearing seat for the tension member, the depression of the metal to form said seat creating upper and lower forwardly projecting parts to engage said member and displacing the metal of the forward end of the strut laterally, whereby said seat crosses the longitudinal planes of said angularly disposed sides, and said sides at their forward portions being otherwise plain and parallel and in their initial form.
3. A brake-beam for railway-cars comprising a compression member, a tension member and a strut of forged metal, said strut being in one integral bar folded on a **U**-bend at the forward end of the strut and forming parallel angularly-set spaced-apart sides connected together at said bend, and the forward end of the strut at said bend being depressed horizontally to form a concave bearing seat for the tension member, and said sides at their forward portions being otherwise plain and parallel and in their initial form.
4. A brake-beam for railway-cars comprising a compression member, a tension member and a strut of forged metal, said strut being in one integral bar forming means for connecting the strut with the compression member and also parallel angularly-set spaced-apart sides, the forward end of the strut being depressed horizontally to form a concave bearing seat for the tension member, the depression of the forward end of the strut displacing the metal at said end laterally beyond the longitudinal planes of said sides and extending said seat laterally across said planes of said sides, and said sides at their forward portions being otherwise plain and parallel and in their initial form.
5. A brake-beam for railway-cars comprising a compression member, a tension member and a strut of forged metal, said strut being in one integral bar folded at the forward end of the strut and forming parallel angularly-set spaced-apart sides connected together at said bend and the ends of the bar being carried upon and to the back of the compression member, the forward end of the strut at said bend being depressed horizontally to form a concave bearing-seat for the tension member, said seat crossing the longitudinal planes of said sides.
6. A brake-beam for railway-cars comprising a compression member, a tension member and a strut of forged metal, said strut being in one integral bar forming parallel angularly-set spaced-apart sides and extending around the compression member, the ends of the bar at the back of the compression member being secured together.
7. A brake-beam for railway-cars comprising a compression member, a tension member and a strut of forged metal, said strut being in one integral bar forming parallel angularly-set spaced-apart sides and extending around the compression member, the ends of the bar at the back of the compression member having respectively an interlocking tongue and a recess for connecting the ends of the bar together.
8. A brake-beam for railway-cars comprising a compression member, a tension member and a strut of forged metal, said strut being in one integral bar forming parallel angularly-set spaced-apart sides and extending around the compression member, the ends of the bar at the back of the compression member being formed with means for interlocking said ends together.
9. A brake-beam for railway-cars comprising a compression member, a tension member and a strut of forged metal, said strut being in one integral bar forming parallel angularly-set spaced-apart sides, a seat for the tension member and at its ends extending around the compression member and being secured together and to said member.
10. A brake-beam for railway-cars comprising a compression member, a tension member and a strut of forged metal, said strut being in one integral bar forming angularly-set spaced-apart sides and a seat for the tension-member and the ends of said bar extending around the compression member and being connected together and secured to said member, the securing means being a recess in the back of said member and a portion of the strut depressed into said recess.
11. A brake-beam for railway-cars comprising a compression member, a tension member and a strut of forged metal, said strut being one integral bar forming parallel angularly-set spaced-apart sides and a seat for the tension-member and the ends of said bar extending around the compression member and having respectively at the back of the compression member a key-tongue and a key-recess for interlocking the ends of the bar together and said strut being secured to the compression member at the back thereof, the securing means being a recess in the back of said member and a portion of said tongue depressed into said recess.

Signed at New York city, in the county of New York and State of New York, this 9th day of June, A. D. 1922.

SETH A. CRONE.
